UNITED STATES PATENT OFFICE.

JERVIS R. HARBECK, OF DETROIT, MICHIGAN, ASSIGNOR, BY MESNE ASSIGNMENTS, TO DETROIT CAN COMPANY, OF DETROIT, MICHIGAN, A CORPORATION OF NEW JERSEY.

PACKAGE-HEADING MACHINE.

1,123,528.

Specification of Letters Patent.

Patented Jan. 5, 1915.

Application filed February 11, 1910. Serial No. 543,390.

To all whom it may concern:

Be it known that I, JERVIS R. HARBECK, a citizen of the United States of America, residing at Detroit, in the county of Wayne and State of Michigan, have invented certain new and useful Improvements in Package-Heading Machines, of which the following is a specification, reference being had therein to the accompanying drawings.

10 The invention relates to machines for securing the heads to the bodies of packages, and particularly for securing a metallic flanged head to a paper or fiber body.

It is the object of the invention to obtain 15 a construction particularly adapted for use with packages of non-circular form, and the invention consists in the construction as hereinafter set forth.

In the drawings—Figure 1 is a plan view 20 of the machine; and Fig. 2 is an elevation thereof partly in section.

In attaching metallic caps to fiber packages, it is usual to provide a flange on the head fitting inside the body and provided 25 with a portion extending over the edge of the body and outer surface thereof. This outer portion is pressed inward by the heading machine, so as to clamp the body and hold the head in engagement.

30 In applying heads to circular bodies, the seaming operation may be performed by the pressure of a roll or disk—movable radially with respect to the axis of the head, but where the head is of non-circular shape it 35 has been found that the work will not be satisfactorily performed by such a construction. Thus where square or oval cans or packages are operated upon, the seaming roll will not instantaneously follow the re- 40 treating part of the surface, which produces a pounding action, with unsatisfactory results.

My present invention involves the discovery that by arranging the movement of the 45 seaming roll in relation to the rotating head support in a path oblique to the common plane of the axis of the seaming roll and rotating head support, perfectly satisfactory results may be obtained in the performance 50 of the work upon oval, square, or other non-circular shapes. The amount of deflection

necessary is comparatively slight but it produces a marked difference in the action and the character of the result. It is however, necessary that the deflection should be toward the advancing side of the work. 55

As shown in detail, A is a rotary head support represented as of rectangular form, B is a seaming pressure roll which is journaled in the shank C, slidably engaging the guides D and yieldably pressed by the spring E.

F is a movable member carrying the roll B and shank C and upon which the guides D are mounted. To the movable member F 65 a lever F' is fixedly secured and forms with the same a bell crank adapted to turn about the stationary pivot F². The outer end of the lever F' is slotted as at F³ for engaging the pin G' upon the handle G pivoted upon 70 a stationary pivot H. Thus, the action of the handle G will rock the member F upon its pivot F² and move the roll B toward or from the rotary head support. The relative arrangement of the parts is such that when 75 the member F is moved to a position in which the roll B performs its work, the guides D will be arranged so that the forward movement of the shank C is in a path at an angle to the common plane of the axis 80 of the seaming roll and rotating head, the deflection being toward the advancing side of the rotating head. I have found that with work of a diameter not to exceed three inches or thereabout, a deflection of the center of the roll one quarter of an inch from the common axial plane of the head support and roll, will produce satisfactory results, but the proper degree of deflection for modified constructions can be best determined 85 by experimentation. 90

In operation, the heads with the bodies in engagement therewith are placed upon the head support A and revolved thereon, while the member F is moved by the handle G to 95 press the roll B in contact with the flange of the head which is to be seamed. During this operation, the roll will be vibrated against the tension of the spring E by the change in radius of the succeeding portions 100 of the head, and it will be noticed that upon the retreating portions of the head the roll

travels backward or opposite to the direction of rotation of the head, which, as has been stated, produces the desired result.

What I claim as my invention is:

5 In a package heading machine, the combination with a rotary head support for non-circular heads, of a seaming roll, a spring for yieldably pressing said seaming roll toward said support, a shank to which said 10 seaming roll is journaled, and a guide for

said shank for directing said roll in a plane deflected from the common axial plane of said head support and roll toward the advancing side of the work.

In testimony whereof I affix my signature 15 in presence of two witnesses.

JERVIS R. HARBECK.
